UNITED STATES PATENT OFFICE.

WILLIAM A. GRAHAM, OF BROOKLYN, NEW YORK, ASSIGNOR TO RADIO CORPORATION OF AMERICA, A CORPORATION OF DELAWARE.

WIRELESS APPARATUS.

Application filed December 2, 1920. Serial No. 427,670.

The present invention relates to an arrangement for establishing circuit connections in a wireless receiving set having a vacuum tube detector and the device will be referred to as an adapter for vacuum tubes.

The object of the invention is to provide a simple inexpensive device which is compact in form and adapted to permit all of the usual connections to be made quickly and conveniently at considerable saving of time to the experimenter. The characteristics of the device render it especially suitable for amateur and experimental use.

The adapter consists of a portable hollow panel or base adapted to rest on a bench, table, or the like, the base being provided with a number of conveniently located binding posts on the exterior for the terminals of various apparatus of the receiving set. The wiring is located in the interior of the base. A vacuum tube socket and several holders for small condensers and a grid leak or other apparatus are also provided on the exterior. At one end I provide a compression screw for a filament rheostat located in the base of the panel together with a number of connections between the various terminals of the posts, holders and socket. The structure combines a number of suitable connections and certain apparatus usually utilized when using a vacuum tube as a detector in a wireless receiving set.

The features which are believed to be characteristic of the invention are set forth with particularity in the appended claims. The invention, however, both as to its organization and method of operation, together with the way in which the particular object thereof may be attained will best be understood by reference to the following description taken in connection with the accompanying drawing in which:—

Fig. 1 is a plan view of the apparatus.

Fig. 2 is a cross section of a binding post.

Fig. 3 is a detail view of a portion of the device.

Fig. 4 is a side view of the apparatus.

Fig. 5 is a bottom view and

Fig. 6 is a diagrammatic view showing the device connected with receiving apparatus.

The panel or base 1 shown in Fig. 1 consisting of any suitable insulating material such as hard rubber or fibre, is hollow and 55 the exterior is provided with a number of

terminals, which may conveniently be binding posts 2 and clamping nuts 3, encased in hard rubber sheaths 4 and 5 respectively as shown in Fig. 2 in cross section. The binding posts which are preferably six in number, 6, 7, 8, 9, 10, 11, project through the base into a cavity which is adapted to contain various connections to be referred to later. The terminals of the input circuit 12 will be connected to binding posts 6 and 7 as shown; the terminals of the filament or "A" battery 13 are connected to posts 6 and 8; the terminals of the regenerative or "tickler" circuit 14 to posts 8 and 10; the terminals of the output or telephone circuit 15 to posts 10 and 11, and the terminals of the plate or "B" battery 16 to posts 9 and 11.

A socket member 17 for the vacuum tube 18 is fitted in an opening preferably located in the center of the space between binding posts 6, 7, 8, 9. In the space between posts 8, 9, 10 and 11 I arrange three sets of terminals 19, 20, 21, 22, 23 and 24. The terminals are preferably in the form of flat spring metal bent into the shape shown in Fig. 3 and having openings adapted to form sockets for the reception of small devices of the form shown in the figure. In the drawings a bridge condenser 25 of cartridge form is shown connected across terminals 19, 20; across terminals 21, 22 a similar grid leak condenser 26 and across terminals 23, 24 a grid leak resistance of high value.

At the end of the panel adjacent the posts 10, 11 for the output phones, I provide a compression screw 27 for a compression rheostat 28 for adjusting the filament current. The compression rheostat as well as all the connections hereafter described are located in the interior of the hollow base previously referred to. A convenient mounting for the compression rheostat comprising an insulating case 29 of hard rubber attached to the interior of the panel by means of screws 30. Suitable plates 31, 32 adjacent to the opposite ends of the rheostat are extended to the surface adjacent the edge of the panel, as shown diagrammatically in Fig. 6.

The bottom of the base is hollow as indicated in dotted lines in Fig. 4 and the hollow space 33 contains various connections which are preferably permanent. The hollow base and connections may thus be con-

veniently placed against any surface such as a table or panel board or the like when in use and may be suitably secured thereto by any well-known and obvious means, for example by screws, nuts and bolts, etc. A vacuum tube detector of a known type having four terminals is preferably used with the adapter and connections are made therewith by means of four contact strips 34, 35, 36, 37 located in the hollow space at substantially right angles to each other. As shown in Fig. 6 each of the contact strips is fitted over a projecting end of a binding post. Contact strip 34, which is adapted to make contact with one filament terminal of the vacuum tube, is electrically connected to post 6 and contact 36 which is adapted to make connection with the other filament terminal is fitted on post 8 but insulated therefrom in any suitable manner. Contact 35 which connects with the grid terminal of the tube is mounted on post 7 but insulated therefrom and the fourth contact strip 37 which contacts with the plate electrode terminal of the tube is mounted in post 9 and electrically connected thereto. Each of the contact strips is retained on the respective posts by means of a nut threaded thereon.

30 A strip 38 electrically connects post 9 to a screw 20' used for fastening the clip 20 to the base and a second strip 39 connects screws 22', 24' which fasten the clips 22, 24 to the base.

35 Insulated wire leads in the interior of the hollow base are used to make the following connections; lead 39 between post 6 and fastening screw 23' of clip 23; lead 40 between spring contact 36 and rheostat plate 31; lead 41 between fastening screw 19' of clip 19 and binding post 10; lead 42 between post 8 and rheostat plate 32; lead 43, between post 7 and strip 39; and lead 44 between spring contact 35 and fastening screw 21' of spring clip 21.

By reference to Fig. 6 it will be noted that by means of the adapter device described I provide a simple arrangement containing all the connection for a three electrode vacuum tube and the amateur or experimenter need only connect various apparatus referred to directly to the binding post, the number of which are reduced to a minimum.

55 I claim:

1. A rheostat socket comprising a base adapted to receive a tube, a rheostat element combined therewith for varying the amount of current supplied to said tube, and a movable clamping element adapted to lock said rheostat element in place.
2. An adapter for establishing circuit connections between a vacuum tube and a wireless set comprising a hollow base, a socket 60 for the vacuum tube on the exterior of the

base, a plurality of contacts for the vacuum tube located in the hollow interior of the base, a plurality of binding posts on the exterior of the base adapted to receive the terminals of the circuits of the wireless set, an adjustable rheostat mounted in the hollow interior of the base, adjusting means for the rheostat on the exterior of the base, and connections in the hollow interior of the base for suitably connecting the contacts and binding posts for establishing circuit connections between the electrodes of the tube and circuits of said wireless set.

3. An adapter for establishing circuit connections between a vacuum tube and a wireless set comprising a hollow base, a socket for the vacuum tube on the exterior of the base, a plurality of contacts for the vacuum tube located in the hollow interior of the base, a plurality of binding posts on the exterior of the base adapted to receive the terminals of the circuits of the wireless set, a plurality of cartridge retaining clips on the exterior of the base having terminals extending into the interior and connections in the hollow interior of the base for suitably connecting the contacts, clips and binding posts for establishing circuit connections between the electrodes of the tube and circuits of said wireless set.

4. An adapter for establishing circuit connections between a three-electrode vacuum tube and a wireless set comprising a hollow base, a socket for the vacuum tube on the exterior of the base, a contact for the grid of the tube, a contact for the plate electrode of the tube, a pair of contacts for the filament terminals, said contacts being located in the hollow interior of the base, a binding post connected to the plate electrode contact, a second binding post connected to one of the filament contacts, a third binding post connected to the other filament contact, a fourth binding post connected to the grid contact, a pair of binding posts for a telephone receiver adapted to be connected to the plate electrode contact and one of the filament contacts, all of said binding posts being located on the exterior of the base, a rheostat mounted on the interior of the base and connected between the filament contacts and connections in the hollow interior of the base for suitably connecting the binding posts and contacts for establishing circuit connections between the electrodes of the tube and the circuits of the wireless set.

5. An adapter for establishing circuit connections between a three-electrode vacuum tube and a wireless set comprising a hollow base, a socket for the tube on the exterior of the base, a contact for the grid terminal of the tube, a second contact for the plate electrode terminal and a pair of contacts for the filament terminals, a binding post on the panel connected to the second contact, a sec-

- ond binding post connected to one of the filament contacts, a third binding post connected to the other filament contact, a fourth binding post connected to the grid terminal 40 contact, a pair of binding posts for a telephone receiver adapted to be connected to the plate electrode contact and one of the filament terminal contacts, all said binding posts being located on the exterior of the 45 base and the connections on the interior of the base, and a pair of terminals on the exterior of the base adapted to support a condenser therebetween and connections in the interior of the base for connecting the terminals 50 with the grid contact and the fourth binding post.
6. An adapter for establishing circuit connections between a three-electrode vacuum tube and a wireless set comprising a hollow 55 base, a socket for the tube on the exterior of the base, a contact for the grid terminal of the tube, a second contact for the plate electrode terminal and a pair of contacts for the filament terminals, a binding post on the panel connected to the second contact, a second binding post connected to one of the filament contacts, a third binding post connected to the other filament contact, a pair of binding posts for a telephone receiver adapted to be connected to the plate electrode contact and one of the 60 filament terminal contacts, all of said binding posts being located on the exterior and the connections on the interior of the base, a pair of terminals mounted on the exterior of the base adapted to support a condenser, 65 the terminals of said socket being shunted across one of the binding posts for the telephone and the plate electrode terminal contact, a second pair of terminals mounted on the exterior of the base adapted to support a high resistance 70 grid leak, the terminals of said socket being in shunt with the second condenser. 75

W. A. GRAHAM.
